UNITED STATES PATENT OFFICE.

DAVID D. FRIEDMAN, OF NEW YORK, N. Y.

BURGLAR-ALARM RELAY-DROP.

No. 852,226.

Specification of Letters Patent.

Patented April 30, 1907.

Application filed May 17, 1906. Serial No. 317,389.

To all whom it may concern:

Be it known that I, DAVID D. FRIEDMAN, a citizen of the United States, and a resident of the city of New York, borough of Manhattan, in the county and State of New York, have invented a new and Improved Burglar-Alarm Relay-Drop, of which the following is a full, clear, and exact description.

This invention relates to certain improvements in relay drops especially useful in burglar alarm systems, and relates more particularly to a new and improved means whereby the armature of an electro-magnet may be locked in position upon the breaking or closing of the circuit.

The device is illustrated in connection with an burglar alarm system, and in such it serves as a relay in closing a second circuit and acts to lock the parts in contact, whereby after the first circuit is broken and the relay operated to ring a bell or give any other suitable alarm the operation of the alarm cannot be interrupted by restoring the first circuit to its original condition.

Reference is to be had to the accompanying drawings forming a part of this specification, in which similar characters of reference indicate corresponding parts in all the figures, in which

Figure 1 is a transverse section through my improved relay drop, said section being taken on the line 1—1 of Fig. 2; Fig. 2 is a transverse section taken on the line 2—2 of Fig. 1; and Fig. 3 is a diagrammatic illustration of a system employing my improved device.

The operating parts of my improved device are preferably supported upon a plate 10 having projections 11, whereby it may be rigidly secured to the wall or in any other suitable location, and the operating parts are protected and concealed by a cover or casing 12 rigidly secured to the base-plate by means of screw bolts 13 or in any other suitable manner. Within the casing are supported the coils 14 of an electro-magnet, the wires 15 and 16 from said magnet leading to binding posts 17 and 18 within the casing. These binding posts extend through the plate 10 and are preferably insulated therefrom, whereby the wires of the burglar alarm or other system may be connected thereto at the rear of the plate 10. Supported adjacent the coils of the magnet is the armature 19 pivotally connected to a pin 20 and normally held out of engagement with the coils by

means of a suitable spring 21. The armature 19 carries a contact spring 22, one end of which is connected to a binding post 23 and the other end of which normally contacts with an adjustable contact screw 24 carried by the casing and connected to a binding post 25.

Mounted upon the casing 12 and extending through an opening therein is a pin 26 having the inner end thereof normally contacting with one of the sides of the armature 19. For more firmly supporting the pin I provide a bracket arm 27 secured to the casing and terminating a short distance therefrom, whereby the pin is supported not only in the end of the bracket arm 27 but also by the wall of the casing. Within the casing and surrounding the pin 26 there is provided a coil spring 28 normally tending to draw the pin into the casing, but inward movement of the pin is normally prevented by the engagement of the inner end of said pin with the side of the armature.

The binding posts 17 and 18 are normally connected to the burglar alarm system, which system is diagrammatically illustrated in Fig. 3. Leading from the binding post 17 is a wire 29 leading to the battery 30, and between said battery and the binding post 18 is arranged a wire 31 leading adjacent the various doors and windows or other points at which the current may be broken by the entry of a burglar. A suitable switch 32 is provided in this wire, whereby the circuit may be broken whenever desired.

Connected to the binding post 24 is a wire 33 leading to a battery 34, and from this battery leads a wire 35 to the alarm bell 36, which latter is connected to the binding post 23 by a wire 37 including a switch 38. When the alarm system is set the current generated in the battery 30 flows continuously through the coils 14 of the electro-magnet and the armature is held in engagement with the ends of the cores of said magnets. As soon as this circuit, hereinafter referred to as "the protecting circuit" is broken, the armature 19 is liberated and moves away from the magnet by the action of the spring 21. The spring contact 22 is forced into engagement with the contact screw 24 and the second or alarm circuit is closed and the bell 36 is rung by the current generated in the battery 34. As soon as the armature moves away from the coils of the magnet, the pin 26 is immediately forced inward, due to the action of the spring

28 and as this pin passes the side of the armature, the latter is prevented from returning into contact with the magnet and the effective closing of the circuit through the contacts 22 and 24 is insured. The pin 26 drops at the same time that the bell begins to ring, so that should the burglar after breaking the protecting circuit instantly close said circuit when he hears the alarm bell ring, he cannot 10 by so doing stop said bell. The bell will continue to ring even though the protecting circuit is closed and cannot be stopped save by throwing the switch 38 or by withdrawing the pin 26, said pin being provided with a 15 suitable handle 39 for accomplishing this purpose.

It is evident that the protecting circuit may, if desired, be an open one and the pin 26 so located that it will be held in place when 20 the armature is away from the magnet and drop in place when the armature is in contact therewith. In this case, the contact 22 would be so constructed that the alarm circuit would be closed upon the energizing of 25 the magnet rather than upon the de-energizing thereof.

Having thus described my invention, I claim as new and desire to secure by Letters Patent:

30 1. In combination, an electromagnet, an armature adapted to occupy a position either in contact with said magnet or spaced therefrom, means for normally holding said armature in one of said positions, and a longitudinally movable pin normally held from movement by said armature when in the last mentioned position and adapted to be released and engage with the side of said armature to prevent the return of the latter after the armature has been moved to its oppositely disposed position.

2. In combination, an electromagnet, an armature adapted to occupy a position in contact with said magnet or spaced therefrom, means for normally holding said armature in one of said positions, means operatively connected to the armature for closing a circuit when said armature is in its oppositely disposed position, and a longitudinally 45 movable locking pin normally engaging with one edge of said armature when the latter is in its first mentioned position and adapted to be released and prevent the return of the armature by the movement of said armature 50 to its oppositely disposed position.

3. In combination, an electromagnet, an armature pivotally mounted adjacent thereto and adapted to occupy either one of two positions, means normally holding said armature in one of said positions, means operatively connected to said armature for closing a circuit when said armature is in its second position, and a spring pressed longitudinally movable pin normally engaging with the edge of the armature when the latter is in one 65 position and adapted to engage with one side of the armature to prevent the return of the armature when the latter is in its second position.

4. In combination, a base plate, an electromagnet mounted thereon, an armature movably mounted adjacent said electromagnet, a casing secured to said base plate and enclosing said armature and electromagnet, and a longitudinally movable pin carried by said 70 casing and normally engaging with said armature.

5. In combination, a base plate, an electromagnet carried thereby, an armature adjacent said magnet and adapted to occupy 80 either one of two positions, means for normally holding said armature in one of said positions, means operatively connected to the armature for closing a circuit when the armature is in the second position, and a longitudinally movable spring pressed pin carried by said casing and normally engaging with the edge of said armature when it is in the first mentioned position, and adapted to engage with the side of the armature to prevent 85 its return movement when the armature is in its second position.

6. In combination, a base plate, an electromagnet mounted thereon, an armature adjacent said magnet and capable of occupying either one of two positions, a casing surrounding said armature and magnet, and a longitudinally movable pin extending through said casing and carried thereby, said pin being normally held in its outermost position when the armature is in one of its two 90 positions and movable into the casing to engage with the side of the armature to prevent its return movement when said armature is in its second position.
